UNITED STATES PATENT OFFICE.

CLAYTON HOBERT, OF PHILADELPHIA, PENNSYLVANIA.

DETACHABLE RUBBER HEEL.

Application filed April 5, 1927. Serial No. 181,140.

My invention relates to a new and useful improvement in detachable rubber heels, and has for its primary object to provide a device of this character which may be readily and quickly removed or replaced, thereby making it possible for a person to replace worn rubber heels with new ones, or change the rubber heels of a pair of shoes, so that the wear will be more evenly disposed and thus increase the life of the rubber heels.

Another object of my invention is to provide an exceedingly simple and effective attaching device for rubber heels which when secured upon the ordinary heel of a shoe will readily guide into place a rubber heel made to coact therewith, and finally lock said rubber heel in position so that it may not be accidentally displaced; and a still further object of my invention is to so construct the attaching device that it will offer a large bearing surface to that portion of the rubber heel which is located thereon so as to avoid chafing or wearing away of that portion of the rubber heel in contact with the locking device, and provide for the entire concealment of the attaching device within the rubber heel, except the thin edge at the surface of the inner curved portion of said heel.

With these and other ends in view, this invention consists in the details of construction and combination of elements herein-after set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1, is a plan view of a rubber heel made in accordance with my present invention.

Fig. 2, is an edge view of Fig. 1 looking in the direction of the arrow adjacent to the latter.

Fig. 3, is a section on the line 3—3 of Fig. 1.

Fig. 4, is a detail perspective view of the attaching device.

In carrying out my invention as herein embodied, 11 represents a rubber heel made in accordance with my improvements, in which two L-shaped grooves 12 are formed longitudinally thereof, opening upon the inner surface of the heel and a locking groove

13 which is here shown as semi-circular in shape.

14 represents the attaching device which is preferably made of sheet metal having the L-shaped flanges 15, and adapted to pass into the L-shaped grooves 12, and also having a locking member 16, which latter is adapted to engage the groove 13. This attaching device has two or more holes 17 formed through the body thereof, through which nails or screws are driven for securing it to the ordinary heel of a shoe. The heel 11 also has an inclined surface 18, which surface is below the general level of the inner surface of the heel to facilitate the attaching of the rubber heel to the attaching device, as hereinafter set forth.

From the foregoing description, it will be obvious that after the attaching device 14 has been secured in proper position upon the bottom of the ordinary heel of a shoe, that the rubber heel may be readily applied thereto by positioning the L-shaped slots 12 over the L-shaped flanges 15, and forcing the heel forward, during which process, the locking member 16 will ride upon the inclined surface 18 and deflect the rear portion of the heel downward so that when this locking member registers with the groove 13, said groove will be snapped over this locking member, and thereafter the rubber heel will be securely held against accidental displacement; and on account of the circular shape of the locking member, a relatively large surface is provided for sustaining the shocks incident to walking, and thus prevent chafing or the wearing away of the wall of the groove 13. This is of considerable importance in practice, since heavy strains and shocks are brought to bear upon the fastening device and those portions thereof which maintain the heel in position.

When the rubber heel is in place only the thin edges of the fastening device appear flush with the inner edge of the heel, as shown in Figs. 1 and 2, and thus the appearance of the heel is not marred by the prominent display of metal upon the outer surfaces thereof.

When it is desired to remove the rubber heel, it is only necessary to spring the rear portion thereof downward sufficiently to disengage the groove 13 from the locking member 16 when the heel may be forced rearward, the slots 12 sliding along the L-shaped flanges 15.

By my improved construction a rubber heel is produced which when in place is firmly held against any displacement either longitudinally or sidewise, and yet is quickly and conveniently attachable or detachable since in the attaching of the heel it is guided into accurate position by the flanges 15, and the rear portion thereof is sprung downward by the riding of the locking member upon the inclined surface 18.

Of course I do not wish to be limited to the exact details of construction as herein shown as these may be varied within the limits of the appended claims without departing from the spirit of my invention.

Having thus fully described my invention, what I claim as new and useful is:

1. In a rubber heel for shoes, an attaching device comprising two guiding flanges and a locking flange in combination with a rubber heel having guiding grooves therein adapted to slide over the guiding flanges of the attaching device, a locking groove adapted to engage the locking flange, and an inclined surface leading from the inner edge of the heel and terminating at the locking groove, said inclined surface serving to coact with the locking flange for riding the rear portion of the heel downward until said locking flange registers with the locking groove.
2. The herein described combination of a

fastening device adapted to be secured to the under side of a shoe heel, said fastening device having two L-shaped guiding flanges and a locking flange; and a rubber heel having longitudinal L-shaped grooves corresponding in cross section to the L-shaped flanges of the attaching device and also having a locking groove corresponding in shape to the locking flange, and an inclined surface formed upon the inner surface of said heel for flexing the rear portion of the heel when the latter is forced over the guiding flanges.

3. In a detachable heel, the combination of an attaching member comprising parallel L-shaped guiding flanges, and a semi-circular locking flange arranged transversely of the guiding flanges and spaced to the rear thereof, said locking flange extending substantially the complete distance between the guiding flanges, and a rubber heel having L-shaped grooves for registration with the guiding flanges and also having a locking groove in spaced relation to the L-shaped grooves for registration with the locking flange and further having an inclined surface formed in the inner face and extending from the forward edge of the heel to said locking groove.

In testimony whereof, I have hereunto affixed my signature.

CLAYTON HOBERT.
